DANIEL W. B. KURTZ, JR., OF COLUMBIA, MISSOURI

RECORD OR INDEX CARD

Application filed March 27, 1928. Serial No. 265,090.

It has long been common to employ, in connection with books in libraries and names and ages in life insurance and under various other conditions, cards serving as indexes adapted to be grouped together and separated with ease. My invention relates to an improvement in the cards whereby they can be handled or "fingered" in an easier and more rapid manner. It is the common experience of the users of these cards that in "fingering" them, it is often necessary, in order to arrive at the desired one, to separate and take three or four, which stick together, from the others in the file, and slide them apart with the moistened thumb before the desired one can be exposed to view. This sticking together is largely due to the contact of the surfaces and the consequent lack of air between the cards. I have discovered that it is possible and very practical to have the "fingered" edges of the cards always a little ways apart by beveling these edges, which are the upper and the end edges of the cards. The bevels which I propose are to be on the back side of these edges, and therefore the entire front, or face, of the card is thus left plain, so as to be written or printed upon as usual. The purpose of beveling these edges of the cards is to render them more easily separable by the searcher's finger tip when separating the cards while searching for the desired card. My proposed beveling of the "fingered" edges of the cards render possible this desired result by producing a small permanent open space between the "fingered" edges, which permanent open space affords the searcher's finger tip an "inning" between these edges, which "inning," being permanent, is readily and easily found.

The following is a description of what is considered the best means of carrying out the invention.

45 The accompanying drawings are a part of this specification.

Fig. 1 is a front plan view of one of my improved cards.

50 Fig. 2 is a back plan view of one of my improved cards.

Fig. 3 is an end view of a plurality of my cards assembled.

Fig. 4 is a top plan view of a plurality of my cards assembled.

Referring to the drawing *a* represents the body of an index card provided with rearwardly extending bevels *a'* on its top and end edges; *b* indicates a similar card, having similarly located bevels *b'*, and *c*, *d*, and *e* are other similar cards, each having respectively similar bevels *c'*, *d'* and *e'*.

By reason of this structure of the index card, with rearwardly directed bevels, the cards when assembled, as shown in Figs. 3 and 4 with their bevels extending rearwardly, are separated by grooves defined by the said bevels and the marginal portions of the face of the adjacent card into which grooves an operator can readily insert the tip of a finger nail to quickly and accurately separate the cards, either from the top or from either end.

The bevels, being on the back side only of the card, leave the entire front side, or face, of the card undisturbed, plain and ready for the written or printed matter which the card is intended to carry in the files. The beveling is not to be of the lower edge of the card, as this edge is never "fingered" when separating the cards in making a search for the desired card, but to the top and end edges which are the edges that are "fingered" when the search is being made. Furthermore, it will be apparent that by reason of the location of the bevels on the backside only of the card the said bevels are effective even when only two cards are assembled.

The method of beveling these edges of the cards may be by a "sloping" cut of the edges when the cards are cut from larger sheets of the paper from which the cards are made; or it may be by "rolling" the edges under heavy pressure rollers after the cards are cut out from the larger sheets of paper from which they are made. This latter method will produce harder and more durable beveled edges than the former method. If desired, a hardening substance may be used by keeping the knife or the rollers moistened with it during their use. The card with the bevels produced merely by the cutting proc-

ess I think however would have edges sufficiently durable for all ordinary usage of index or record cards.

I claim as my invention—

5 1. In a card index, a series of record cards beveled along the back side of the top and end edges of the cards, substantially as herein specified.

10 2. In a card index, a series of record cards having rearwardly beveled edges for easy accessibility and quick handling.

In testimony that I claim the invention above set forth I affix my signature hereto.

DANIEL W. B. KURTZ, JR.
